United States Patent Office

Des. 227,518
Patented July 3, 1973

227,518

PONCHO

Theodore D. A. Collet, 6140 Calle Tuberia,
Scottsdale, Ariz. 85251

Filed May 18, 1971, Ser. No. 144,705

Term of patent 14 years

Int. Cl. D2—02

U.S. Cl. D2—179

FIG. 1 is a front elevational view of a poncho showing my new design in wearing position, the broken line outline of a wearer is for purposes of illustration only;

FIG. 2 is a front elevational view thereof on a reduced scale showing my new design in a tent like position; and

FIG. 3 is a rear elevational view.

I claim:

The ornamental design for a poncho, as shown and described.
